ABSTRACT

A sharpening tool for the sharpening of single and double-beveled edge knives, broadhead arrows and related implements. The sharpener comprises a body with a handle, a handguard, and recesses for detachably mounting pairs of rectilinear sharpening and non-sharpening elements. The recesses are adapted so that a pair of mounted elements form a "V" shaped cutting angle of a constant degree. The pair of elements comprises two sharpening elements for double-beveled edge blades, and one sharpening element and one non-sharpening rest element for single-beveled edge blades. The "V-shaped" cutting angle formed by the mounted elements is imparted to a knife edge being sharpened, and accordingly the degree of angle is defined as the optimal blade edge cutting angle. The recesses are further adapted so that the overlapping sharpening and non-sharpening elements do not contact each other, preventing the elements from vibrating against each other and thereby extending the useful life of the elements. The point of coincidence of the cutting angle vertex upon the elements preferably occurs substantially spaced from the element edge midpoints, thereby enabling each element edge to provide two distinct sharpening areas when the elements are exchanged and the same element edges are rotated to form the cutting angle. In one embodiment the handguard is adapted to provide planar surfaces for placing the tool upon a table or similar working area while utilizing the tool, and the handguard is further adapted to allow a user to reposition or remove and replace the handguard.

SHARPENER FOR SINGLE AND DOUBLE-SIDED BLADES

CROSS REFERENCE TO RELATED APPLICATION

This application is a continuation-in-part of a previous application filed in the United States Patent and Trademark Office by us, Theodore Kenesky and James J. Kenesky, on Oct. 17, 1998, titled "Knife and Broadhead Blade Sharpener" and assigned Ser. No. 09/174,112, now U.S. Pat. Ser. No. 6,142,038.

FIELD OF THE INVENTION

This invention relates generally to the sharpening of cutting edges of tools, such as knives and arrow heads, and more particularly to a hand held sharpening device for such tools. The invention can sharpen both single and double-sided blades.

BACKGROUND INFORMATION

As long as mankind has utilized sharpened devices and cutting instruments such as knives and blades there has been a need for methods and devices for keeping those devices sharp.

Many sharpening devices have been proposed over the years, utilizing a wide variety of sharpening blade shapes and sharpening angles. Some sharpeners utilize round sharpening blades, such as U.S. Pat. No. 4,112,790 to Marder, and U.S. Pat. No. 5,377,563 to Weeks. Due to the radial nature of the sharpening blades these devices do not provide a true "V" shaped edge to the sharpened device, and therefore do not achieve the best shape or durability for the sharpened workpiece.

Other devices rely upon abrasive-type sharpening elements, such as U.S. Pat. No. 4,530,188 to Graves. However, due to the inherently inexact nature of the shape of the sharpening elements, and in particular as extended use wear causes the shape to change, these type of devices also are unable to ensure that the optimal "V" shaped edge results.

Sharpeners have been proposed that utilize beveled metallic sharpening elements, in a variety of shapes. For triangular elements, see U.S. Pat. No. 4,599,919 to Fortenberry, and U.S. Pat. No. 562,223 to Hausse. For square elements, see U.S. Pat. No. 584,933 to Friedrich. While previously proposed devices of this type can obtain the desired "V" shaped edge, they do not precisely position the sharpening elements to provide the best degree of angle to the sharpened edge. And while some allow the sharpening elements to be rotated or exchanged to provide fresh sharpening edges, they do not increase the sharpener element utilization. They also do not increase the useful life of the sharpening elements.

SUMMARY OF THE INVENTION

According to the present invention a sharpening tool is provided which comprises a body with recesses for detachably holding sharpening elements. The recesses are shaped to hold the sharpening elements in a fixed position with respect to each other so that the angle of intersection of the elements is a precise fixed value, thereby ensuring a fixed value for the resultant sharpened workpiece edge shape. Preferably the sharpening elements have sharpening edges which have a point of coincidence with respect to each other located along the sharpening edges between their midpoints and one of their ends, so that exchanging and rotating the

detachable elements results in each sharpening edge of each element providing two distinct sharpening points, doubling the useful life of the edges as compared to previously proposed sharpeners. The elements are also spaced so that they do not contact each other while sharpening a work piece; this prevents the elements from vibrating against each other while sharpening a work piece, and therefore prevents vibration related cracking and chipping of the elements. Preferably a removable, adjustable handguard is also provided.

10 The invention is also adaptable to sharpen a single-sided or single-edged cutting blade. This type of blade has a cutting edged formed by beveling on one side of the cutting element. Examples are common household scissors, and cutting shears. The invention is adapted by replacing a sharpening element with a non-sharpening "rest" for receiving the side of the blade opposite the beveled side.

BRIEF DESCRIPTION OF THE DRAWINGS

- 20 FIG. 1 is a perspective view of one embodiment of a sharpening device according to this invention;
- FIG. 2 is an exploded perspective view of the proximal end of the device of FIG. 1;
- 25 FIG. 3 is a side elevation view of the proximal end of the device of FIG. 1;
- FIG. 4 is a top plan view of the proximal end of the device of FIG. 1;
- 30 FIG. 5 is a perspective view of another embodiment of a sharpening device according to this invention; and
- FIG. 6 is a perspective view of another configuration of one of the sharpening elements of this invention;
- 35 FIG. 7 is a perspective view of a blade rest according to the present invention;
- FIG. 8 is a side elevation view of the proximal end of a device according to the present invention comprising the rest of FIG. 7 and one of the sharpening elements of the present invention.

DESCRIPTION OF THE PREFERRED EMBODIMENT(S)

40 Referring now to the drawings, and for the present to FIGS. 1 and 2, a sharpening tool is provided which has a unitary cylindrical body 10 with integral handle 12 at a distal end 11, and sharpening element recesses 14a and 14b at a proximal end 13 for receiving sharpening elements 18a and 18b. A recess area 16 is also provided at the proximal end for reception of a workpiece W, such as a knife blade. The sharpening elements 18a and 18b are removably secured against outer planar mounting surface 20a and inner planar mounting surface 20b respectively in the recesses 14a and 14b by screws 22a and 22b passing through holes 24a and 24b in sharpening elements 18a and 18b and threaded into threaded apertures 26a and 26b in the proximal end 13. A handguard 32 is removably positioned on the body 10 between the distal and the proximal ends, the construction of which will be described presently.

45 The handle 12 is cylindrical in shape, with an outside diameter preferably of about 0.5 inches. It may be securely held in one hand, thereby allowing a single user to utilize the sharpener while that user's other hand manipulates the workpiece to be sharpened. The example depicted in the accompanying drawings uses anodized aluminum for the tool body 10, with the surface of the handle 12 knurled to provide a non-slip grip surface for the user.

50 Referring now to FIGS. 1, 2 and 3, the points of contact between the workpiece W being sharpened and the sharp-

ening edges **44a** and **44b** of sharpening elements **18a** and **18b** respectively is a common point of coincidence **70** on cutting edges **72a** and **72b** as viewed along the edge of the workpiece **W**. As shown in FIG. 3, the intersection of the cutting edges **72a** and **72b** of sharpening elements **18a** and **18b** respectively at the point of coincidence **70** defines a "V"-shaped cutting angle **80**. Drawing the workpiece **W** through the sharpening tool at this point of coincidence **70** with the cutting edges **72a** and **72b** as the leading edges causes the cutting edges **72a** and **72b** to hone the workpiece by removing material from both sides of the workpiece **W** blade edge: accordingly, this embodiment of the invention is adapted to sharpen "double-edged" blades. Since the cutting edges **72a** and **72b** are linear, the resultant honed edge has a shape substantially equivalent to the cutting angle **80**. An important feature of the invention is that the sharpening elements **18a** and **18b** secured against the planar mounting surfaces **20** and **20b** in the recesses **14a** and **14b** by screws **22a** and **22b** have their rotation about said screws **22a** and **22b** constrained by retaining structures **34a** and **34b**, and **36a** and **36b**, thereby defining the cutting angle **80** as a constant value. In the example depicted in FIG. 3 the structures **34a** and **34b** abut against two edges of sharpening element **18a**, and structures **36a** and **36b** abut against two edges of sharpening element **18b**, thereby precluding rotation of the elements upon their planar mounting surfaces **20a** and **20b**.

By defining the cutting angle **80** as a constant value, this value can be specified to provide optimal blade sharpening results, since a resultant honed edge imparted to a blade sharpened by the device has a shape substantially equivalent to the cutting angle **80**. The bevel angle of a blade is defined as the angle between the two surfaces that form the cutting edge. For a single bevel-edged blade, where one side of the blade is beveled and the other side is flat, the optimal angle of bevel for sharpness and durability is twenty (20) degrees, although any fixed value within a range of about nineteen (19) through about twenty-one (21) degrees will produce good results. For a blade that has two opposing beveled edges, also known as a double-edged blade, the optimal total angle of bevel is therefore about forty (40) degrees, although any fixed value within a range of about thirty-eight (38) through about forty-two (42) degrees will produce good results. Accordingly, the cutting angle **80** as shown in FIG. 3 is preferably from about 38 to 42 degrees, and more preferably about forty degrees. Those skilled in the art may find other values appropriate for their particular applications of this device.

Although not required to practice the invention, it is preferable that the two sharpening elements **18a** and **18b** are identical in shape and size, and therefore interchangeable. A preferred sharpening element shape is rectilinear, as FIG. 2 illustrates. Another preferred shape is the square sharpening element **19** shown in FIG. 6. Moreover, it is readily apparent that the elements **18a** and **18b** can be detached, turned over, and reattached, so that the beveled edge of the elements faces away and downward when the sharpener is oriented as shown in FIG. 3 (this configuration not shown). This alternate orientation allows a user to draw a blade to be sharpened in the opposite direction when compared to the orientation shown in FIG. 3. A preferred composition of the sharpening elements **18a** and **18b** is tungsten carbide. The sharpening edges **44** are beveled surfaces, and the preferred angle of bevel for long life of the beveled edge and optimal workpiece sharpening is a value between about 5 degrees and about 15 degrees, the more preferable value being about 12 degrees.

It is important that the mounted sharpening elements **18a** and **18b** do not contact each other while sharpening a

workpiece, otherwise vibrations communicated between the two elements while under the tension caused by sharpening the workpiece can cause the elements to prematurely fail by cracking and chipping. As shown in FIG. 4, the mounted first sharpening element **18a** overlaps but does not touch the mounted second sharpening element **18b**, these elements being separated by a gap **62**. Referring now to FIGS. 2 and 4, this gap **62** is achieved by defining the planar mounting surfaces **20a** and **20b** of sharpening element recesses **14a** and **14b** respectively as lying on spaced parallel planes, the spacing distance being a value equal to the maximum allowable width of the sharpening element **18b** plus a constant. This constant preferably should be between about 0.003 and about 0.005 inches, and more preferably about 0.003 inches. The width of the embodiment of sharpening element **18b** in FIG. 4 is about 0.060 inches wide, the gap **62** is about 0.003 inches wide, and accordingly the spacing distance between the planar mounting surfaces **20a** and **20b** is about 0.063 inches. It is readily apparent that other sharpening element embodiments of less than 0.060 inches in width may be used with the device of FIG. 4. It is also apparent that other mounting surface spacing distances, and as a result other sharpening element widths, may be practiced with the invention. Although sharpening elements of identical dimensions may be used for both elements **18a** and **18b**, allowing them to be freely interchanged, it is important that the width of sharpening element **18a** is not limited to the spacing distance plus a constant: this allows other elements of lesser or greater width and dimensions relative to element **18b** to be used for element **18a**, as will be discussed later in this specification.

Referring now to FIGS. 1 and 3, the point of coincidence **70** is located on the cutting edges **72a** and **72b** of sharpening elements **18a** and **18b** respectively about midway between cutting edge midpoints **74a** and **74b** and cutting edge ends **76a** and **76b** respectively. This location enables the user to achieve two points of coincidence **70** on each cutting edge **72** through the following method: by detaching both sharpening elements **18a** and **18b**, rotating and reattaching them with their positions on the sharpener exchanged and the same cutting edges **72a** and **72b** again intersecting at the point of coincidence **70**, the point of coincidence **70** now engages the cutting edges **72a** and **72b** at points about midway between their edge midpoints **74a** and **74b** and their other respective ends **78a** and **78b**. Accordingly, previously unused areas of the same sharpening edges **44a** and **44b** will now be used in honing a workpiece. Thus the square sharpening element **19** of FIG. 6 with four sharpening edges **44** provides eight distinct sharpening points of coincidence **70**, and the rectilinear sharpening element **18** of FIG. 2 with two sharpening edges **44** provides four sharpening points of coincidence **70**. Although the embodiment shown in FIGS. 1 and 3 locates the point of coincidence **70** above the midpoints **74a** and **74b**, an alternative embodiment of the invention (not shown) may locate the point of coincidence **70** below the midpoints **74a** and **74b**.

As shown in FIG. 5, the handguard **28** has a circular mounting aperture **30** for the reception of the body **10**. It is important that the aperture **30** have an inside diameter value about 0.001 inches less than that of the body **10** outside diameter. With the screws **22a** and **22b** and the sharpening elements **18a** and **18b** removed from the body **10**, the proximal end **13** of the body **10** is inserted into the aperture **30** and the handguard **28** is then press-fit onto the body **10**. The handguard **28** is made of a resilient material such as hard plastic. The difference in the inside diameter of the mounting aperture **30** with respect to the body **10** outside

diameter causes the resilient handguard 28 material to exert pressure upon the body 10, and this pressure results in a frictional force that resists movement of the mounted handguard 28 with respect to the body 10, thereby keeping the handguard 28 in a fixed position with respect to the body 10. The circular style handguard 28 depicted in FIG. 5 maximizes the portability of the tool, enabling the device to be readily stored in toolboxes, glove compartments, kitchen drawers and the like; it also gives the device a pleasing visual design.

The handguard 32 shown in FIG. 1 is generally arch shaped having a slot 43 defining two legs 40a and 40b ending in flat planar surfaces 42a and 42b. The surfaces 42a and 42b enable the sharpener to be placed firmly upon a work surface, such as a table, kitchen counter or workbench, while a workpiece is being sharpened. Each leg 40a and 40b also has a semicylindrical mounting notch 46a and 46b. The proximal end 13 of the body 10 is inserted into the slot 43 between the mounting notches 46a and 46b. The slot 43 is adapted so that the screws 22a and 22b and the sharpening elements 18a and 18b freely pass through the slot 43, and therefore need not be removed, as the handguard 32 is slid off of or onto the body 10. The mounting notches 46a and 46b preferably have a radius value between about 0.001 inches and about 0.005 inches greater than that of the body 10 radius, thereby enabling the body 10 to be freely inserted into or removed from the handguard 32 by hand. This allows a user to reposition, remove or replace the handguard without undue force or special tools, by operating the fastening device described below.

As shown in FIG. 1, a self-tapping #6 flat head sharp point trim screw 52 passes through a cylindrical aperture 58 having a diameter of about $\frac{1}{32}$ inch or greater, the slot 43, and engages a cylindrical reception bore 60 having a diameter of about $\frac{1}{8}$ inch. The diameter of aperture 58 is larger than the thread diameter of the screw 52, thereby allowing the screw 52 to pass freely through the aperture 58. The threads of self-tapping screw 52 engage the walls of reception bore 60, and thereby cut into the walls of reception bore 60 when the screw 52 is inserted into reception bore 60 with a clockwise rotation. The screw 52 is rotated clockwise and thereby drawn into the bore 60 as the screw threads cut into said bore, until the screw head 54 firmly engages the screw head recess 56. Turning the screw 52 clockwise after the screw head 54 has firmly engaged the screw head recess 56 causes the screw head 54 to force the arch leg 40a toward arch leg 40b, thereby drawing mounting notch 46a towards mounting notch 46b, causing said notches to exert pressure upon the body 10. As a result of this pressure, frictional forces between the handle mounting notches 46a and 46b and the body 10 keep the handguard 32 position fixed with respect to the sharpener body 10. The handguard 32 is made of a resilient material, for example a hard plastic. When screw 52 is turned counterclockwise, the resiliency of the handguard 32 returns the arch legs 40a and 40b to their normal position with respect to each other, diminishing the pressure of mounting notches 46a and 46b upon the body 10, thereby reducing the frictional forces holding the handle 29 in a fixed position with respect to body 10, and therefore allowing a user to reposition, remove or replace the handle 29.

Referring now to FIG. 7, a rest 82 according to the present invention is shown. The rest 82 enables the invention to sharpen a single-sided or single-edged cutting blade formed by beveling on one side of the blade. Examples are common household scissors, and cutting shears. FIG. 8 shows a detail view similar to that of FIG. 3, depicting the invention of

FIGS. 1 through 5 with the rest 82 replacing the outer sharpening element 18a. The rest 82 has a flat non-beveled guide edge 84 for receiving the side of the blade opposite the beveled side of the blade being sharpened. The guide edge 84 does not cut or otherwise sharpen the non-sharpened side of a blade as it is drawn along it, but instead serves as a sliding surface for a blade drawn through the tool. The rest 82 may be fabricated from a variety of materials, such as brass, bronze or steel metallic compounds. The rest 82 may also be fabricated from a plastic material, such as a hardened plastic compound. Since the rest 82 is located on top of the sharpening element 18, on the outer mounting surface, the maximum width of the rest 82 is not limited to the spacing distance between the mounting surfaces 20a and 20b less the gap distance 62. However, in a preferred embodiment, the width of the rest 82 is limited to a maximum width of the spacing distance between the mounting surfaces 20a and 20b less the gap distance 62, and is therefore able to be reversed and mounted instead on inner mounting surface 20b (this configuration not shown).

Referring again to FIG. 7, it is important that the guide edge 84 is not parallel with the opposite edge 86, but is offset with respect to the opposite edge 86 at an angle 88. Referring again to FIG. 8, the offset angle 88 reduces the cutting angle 90, formed by the intersection of the sharpening element 18 and the rest 82, to a preferred cutting angle for single blades. The offset angle 88 is preferably between about nineteen (19) and about twenty-one (21), and more preferably about twenty (20) degrees, and as a result the cutting angle 90 is between about nineteen (19) and about twenty-one (21), and more preferably about twenty (20) degrees. As discussed previously in this specification, the optimal angle of intersection for sharpening single-sided blade edges is about twenty (20) degrees, although any fixed value within a range of about nineteen (19) through about twenty-one (21) degrees will produce good results. Those skilled in the art may find other values appropriate for their particular applications of this device.

The rest 82 may be designed so that the common point of coincidence 92 between the sharpening element edge 72 and the rest guide 84 is above or below the midpoint of the sharpening edge 72, as discussed above. Alternatively, the common point of coincidence 92 may occur at the midpoint of the sharpening element edge 72, providing another useful sharpening area along the sharpening edge 72.

A portion of the disclosure of this patent document contains material to which a claim for copyright is made. The copyright owner has no objection to the facsimile reproduction by anyone of the patent document or patent disclosure, as it appears in the Patent and Trademark Office patent file or records, but reserves all other copyright rights whatsoever.

While preferred embodiments of the invention have been described herein, variations in the design may be made, and such variations may be apparent to those skilled in the art of making tools, as well as to those skilled in other arts. The materials identified above are by no means the only materials suitable for the manufacture of the tool, and substitute materials will be readily apparent to one skilled in the art. The scope of the invention, therefore, is only to be limited by the following claims.

What is claimed is:

1. A sharpening tool, comprising:
  - a) an elongated body having a front end and a handle end, said front end further comprising a top area for insertion of a workpiece blade for sharpening;

- b) said front end including an inner planar mounting surface and an outer planar mounting surface, said mounting surfaces lying on spaced parallel planes with respect to each other;
  - c) said front end further including two linear inner restraining structures associated with the inner planar mounting surface;
  - d) said front end further including two linear outer restraining structures associated with the outer planar mounting surface;
  - e) a first blade engagement member having upper and lower planar surfaces and a plurality of linear edges, the first blade engagement member lower planar surface detachably mounted to the inner mounting surface, at least two of the linear edges engaged by the inner restraining structures, said first blade engagement member further having a thickness less than the distance between said mounting surface spaced parallel planes;
  - f) a second blade engagement member having a planar surface and a plurality of linear edges, the second blade engagement member planar surface detachably mounted to said outer mounting surface, at least two of the second member linear edges engaged by the outer restraining structures;
- wherein at least one first member edge and at least one second member edge are overlapped and spaced from each other and define a cutting angle having a bottom vertex and two top endpoints within said front end top area for sharpening a workpiece blade; and
- wherein said cutting angle is a fixed value, said value held constant by the restraining structures, which constrain movement of the sharpening members relative to each other.
2. The sharpener of claim 1 wherein the overlapping first member and second member edges each have a midpoint

- and top and bottom ends, each of said midpoints dividing each edge into two edge halves, and said cutting angle vertex is located at a point along each edge about midway between said edge midpoints and one of said top and bottom ends.
5. 3. The sharpener of claim 2 wherein said cutting angle vertex is located at a point along each edge about midway between said edge midpoints and said top endpoints, and therefore within the one-half of each sharpening edge positioned toward the top of the front end top area.
10. 4. The sharpener of claim 2 wherein said cutting angle vertex is located at a point along each edge about midway between said edge midpoints and said bottom endpoints, and therefore within the one-half of each sharpening edge positioned toward the bottom of the front end top area.
15. 5. The sharpener of claim 1 further comprising a handguard attached to the body.
20. 6. The sharpener of claim 5 wherein said handguard member further comprises a planar mounting surface for placement upon a work surface, and a tightening device for tightening the handguard about the sharpener body.
25. 7. The sharpener of claim 1 wherein the overlapped first member edge and second member edge are both beveled cutting edges for sharpening a workpiece blade drawn across it.
30. 8. The sharpener of claim 7 wherein the beveled sharpening edges have a surface angle of bevel between about 5 and about 15 degrees.
35. 9. The sharpener of claim 7 wherein said cutting angle is a value of between about 38 and about 42 degrees.
10. 10. The sharpener of claim 1 wherein one of the overlapped first and second member edges is a beveled cutting edge for sharpening a workpiece blade drawn across it, and the other is a non-sharpening flat guiding edge.
11. The sharpener of claim 10 wherein said cutting angle is a value of between about 19 and about 21 degrees.
